UNITED STATES PATENT OFFICE.

CHARLES L. GOODRUM, OF NEW YORK, N. Y., ASSIGNEE, BY MESNE ASSIGNMENTS, TO
WESTERN ELECTRIC COMPANY, INCORPORATED, A CORPORATION OF NEW YORK.

TELEPHONE-EXCHANGE SYSTEM.

1,209,834.

Specification of Letters Patent. Patented Dec. 26, 1916.

Application filed May 10, 1915. Serial No. 27,053.

To all whom it may concern:

Be it known that I, CHARLES L. GOODRUM, citizen of the United States, residing at New York, in the county of New York and State of New York, have invented certain new and useful Improvements in Telephone-Exchange Systems, of which the following is a full, clear, concise, and exact description.

This invention relates to telephone exchange systems and more particularly to automatic ringing systems for party lines connected with an automatic telephone exchange.

The object of this invention is to provide a system whereby upon the establishment of a connection between two parties connected to the same line, under the control of a simple switching device controlled preferably by the subscriber's switchhook, ringing currents are applied to said line for signaling both parties.

The drawings represent schematically a telephone system embodying this invention, only as much being shown of the circuits and apparatus as is necessary for the clear understanding of this invention.

There are four parties, A, B, C and D connected in multiple to a line 1, 2. Upon the initiation of a call and the sending out of impulses at either station, line 1, 2 is extended by means of automatic switches (not shown) to a connector switch 6 in the well known manner. Each of the parties A-D is given instructions as to how many impulses he is to send out in order to establish a connection with a party connected to his line.

As well known, in a four party-line system ringing current sources of four different frequencies are provided for the signaling of the parties. Supposing for instance that there are current sources of 16, 33, 50 and 66 cycles for signaling parties A, B, C and D respectively, it will be seen that six combinations (16-33, 16-50, 16-66, 33-50, 33-66, 50-66) of these current sources, will make possible the simultaneous signaling of any two parties. The ringing current sources of 16 and 33 cycles are adapted to be connected through the first set of terminals of a selector switch 6, 16 and 50 cycles through the second set of terminals, 16-66 through the third, etc.

If party A desires to obtain connection with party B he sends out impulses for caus-

ing the extension of line 1, 2 to the wipers 3, 4, 5 of selector switch 6, and then by means of an additional impulse sets wipers 3, 4 and 5 of the selector switch 6 on terminals 7, 8 and 9 respectively. A circuit is closed from grounded battery 11 through both windings of relay 12 and wipers 13, 14 of a side switch associated with selector 6, and then through the calling subscriber's loop. Relay 12 becomes energized and by attracting its armature causes the energization of slow acting relay 15. The calling party A thereupon restores his receiver to the switchhook causing thereby the deenergization of relay 12. A circuit is now closed from ground through the armature and back contact of relay 12, armature and front contact of slow acting relay 15, and the winding of escapement magnet 16 to grounded battery. Under the control of magnet 16, wipers 13, 14 and 17 of the side switch are stepped into the second position. Shortly after the energization of magnet 16, relay 15 becomes deenergized. A circuit is now closed from ground through wiper 13, the subscriber's loop, wiper 14, the winding of ringing relay 20 and interrupters 21 and 22 to the two sources of ringing current 23 and 24, one of which is of 16 cycles for ringing party A and the other one of 33 cycles for ringing party B. Under the control of interrupters 21 and 22 the two kinds of ringing currents are alternatively applied to line 1, 2. In this position of the side switch relay 25 cannot become energized, its winding being short-circuited through the armature and back contact of ringing relay 20.

As soon as the calling and called subscribers remove their receivers from the switchhook, relay 20 becomes energized, removes the shunt from the winding of relay 25 and this relay becomes energized, its circuit being closed from ground through wiper 17, winding of relay 25 and resistance 26 to grounded battery. Upon the energization of relay 25 a circuit is closed from ground through wiper 17, armature and front contact of relay 25, and the winding of escapement magnet 16 to grounded battery. Magnet 16 moves the side switch wipers into their third position. In this position of the side switch, relay 25 and, thereby, magnet 16 become deenergized and the ringing circuit is opened. A circuit is now closed through

the subscriber's loop, wipers 13, 14 over relay 12 and this relay again becomes energized, energizing in turn the slow acting relay 15.

5 In the third position of the side switch, subscribers A and B may converse, talking current being supplied to their stations from battery 11 through resistances 30 and 31.

After the conversation is finished and parties A and B have restored their receivers, relay 12 again becomes deenergized and a circuit is closed through the armature and front contact of relay 15 for escapement magnet 16 which moves the side switch 15 wipers into their fourth position. A circuit is now closed from ground through wiper 17, conductor 32, off-normal contact 33 of switch 6, and winding of release magnet 34 to ground battery. Release magnet 34 causes 20 the restoration of selector switch 6 and the side switch associated therewith, the circuit of this magnet being open at 33 as soon as switch 6 reaches its normal position. The ground through wiper 17 is applied also to 25 the release magnets of the switches which are used for extending the connection to selector switch 6, and said switches are restored thereupon to normal in the well known manner.

30 While the invention has been described as applied to a four-party line system, it will be obvious to those skilled in the art that it is equally well applicable to systems in which more or less parties are connected to 35 the same line.

What is claimed is:

1. In a party line telephone system, a line, a plurality of stations connected thereto, a switching device having three operating positions, means for extending said line to said

switching device, signaling current sources of different frequencies, means controlled by said device for associating the current sources with the line, and a switchhook at each station for controlling means for moving said device successively into said positions. 45

2. In a party line telephone system, a line, a plurality of stations connected thereto, a switching device having three operating positions, means for extending said line to said switching device, signaling current sources of different frequencies, a switchhook for each station, means operative upon the first actuation of said switchhook for moving 50 said device into its first position, whereby said current sources are connected with said line, means operative upon a second actuation of said switchhook for moving said device into its second position for disconnecting said current sources, and a releasing means for said device actuated in the third position of said device, following a third actuation of said switchhook. 55

3. In a party line telephone system, a line, a plurality of stations connected thereto, a step-by-step switching device having three operating positions, signaling current sources of different frequencies, a releasing means for said switching device, means controllable at 60 said stations for stepping said device into its various positions whereby the current sources are associated with the line in the first and disassociated from the line in the second, and the releasing means is operated in the 65 third position of said device, respectively. 70

In witness whereof I hereunto subscribe my name this 8th day of May, A. D. 1915.

CHARLES L. GOODRUM.
